UNITED STATES PATENT OFFICE.

MAX MOSLER, OF CINCINNATI, OHIO.

FIRE-PROOF SAFE.

SPECIFICATION forming part of Letters Patent No. 295,272, dated March 18, 1884.

Application filed October 30, 1883. (No model.)

To all whom it may concern:

Be it known that I, MAX MOSLER, a citizen of the United States, residing at Cincinnati, county of Hamilton, State of Ohio, have invented certain new and useful Improvements in Fire-Proof Safes, of which the following is a specification.

The object of my invention is a fire-proof safe which will afford absolute protection in case of fire, and yet be lighter to handle and cheaper to construct than the ordinary fire-proof safe. Its object is also to protect the contents from dampness or injury from the moisture of the fire-proof filling when closed for a long time.

With these objects in view, my invention consists in entirely inclosing the inside of the safe when closed by an air-chamber, which is entirely cut off from the exterior air when the safe is closed, but has free communication with the external air when the safe-door is open.

It consists, also, in certain peculiar arrangements of the inside of the door and bolt-work, all of which will be fully described in connection with the accompanying drawings, and then particularly pointed out in the claims.

Figure 1 is a central vertical section of my improved safe, taken from front to rear of the safe, and looking to the hinge side the door is shown open and in inside plan view, with part of the inside covering-plate removed to expose the bolt-work and means of fastening the plate. Fig. 2 is a horizontal transverse view taken centrally through the closed safe. Fig. 3 is an inside plan view of the form of door and bolt-work I use in constructing double-door safes. In this view the back plate is removed. Figs. 4 and 5 are details showing the manner of locking the back plate to the inner side of the door.

The exterior or frame-work A of the safe is constructed in the usual manner, as is also the door-frame B, except the inner flange through which the bolts pass. The bolt-holes in this inner flange pass entirely through, to communicate with the air-chamber C, which entirely surrounds the body of the inside box, D. This box is secured on the inside flange of the door-frame in the usual manner, and the air-chamber C is formed by a larger box, E, which is secured upon one of the intermediate flanges of the door-frame B.

The bolts F F', instead of being solid, as cus-

tomarily employed, are tubular, to open communication between the chamber in the inside of the door and the chamber C, surrounding the receptacle D, when the door is closed. The bolts F, Fig. 1, are for this purpose open at their inner ends, while the bolts F' are longitudinally slotted at f for the same purpose. The space between the box E and the outer walls of the safe is filled with a non-conducting fire-proof material. The inner flange of the door in the single-door safe, Fig. 1, is beveled off at the corners, and the beveled portion perforated to pass the bolts F, which radiate from the center of the door. The angles of the frame B are also beveled to correspond with the bevel on the inner flange of the door. The beveled corners of the frame are perforated to receive the bolts, which thus communicate with the air-chamber C when the safe is closed. The bolts are shot out from the center of the door and retracted by a slotted cam-disk, G, acting upon pins which project from the coupling-pieces f' into the slots. The cam G is secured upon the bolt-arbor which passes through the door, and is provided with the usual handle or knob upon the outside. The coupling-piece f' is a ring slipped over the end of the tubular bolt F and held to it by a set-screw and an arm projecting from one side of the ring, and having an outwardly-turned end or pin to enter the eccentric slot in the cam-disk G. I prefer to use this separate coupling-piece because it admits of adjustment upon the bolt for the purpose of regulating its throw; but the end of the tubular bolt could be cut away to leave an arm or spur upon the inner end, in which the pin which enters the eccentric slot in disk G could be secured, and thus dispense with the coupling f'. The bolts F are guided radially, when the disk G is turned, by the perforations in the flange of the door and guide-lugs f'', secured upon the lock-plate of the door, which forms the inner wall of the air-chamber in the door, which chamber also contains the lock and bolt-work of the safe. The inner plate, H, (shown broken away in Fig. 1,) is preferably hinged to the flange on the hinge edge of the door. To the inside of the plate H I secure one or more Z-shaped angle-pieces, h which, when the cam G is turned to protrude the bolts, as seen in Fig. 1, will lock the door or plate H against opening. The purpose of this arrangement is to prevent any one from in-

specting the lock (not shown) which dogs the bolt-work, and learning its combination. When the bolts are retracted, the cam G, in retracting them, passes from over the inwardly-projecting 5 arm of the piece h, and the door H may then be opened, so that when it is desired to leave the safe-door open for some time it is only necessary to throw the bolt-work as when the safe is locked, and by turning the lock-arbor dis-10 arrange the combination of the tumblers. Thus the door H can only be opened by those knowing the combination of the lock. The same result will be accomplished in the door having the common form of bolt-work as seen in Fig. 3 by 15 having the button or lug h on the front edge of the inside plate or door to pass between the edge of the inside flange and the bolt-bar f³, so that the bolt-bar will engage its hooked end when the bolts are thrown out.

20 For the purpose of allowing the button to pass inward, the bolt bar is notched, as shown, which notch should be a little larger than the inwardly-projecting end of the fastening piece or button h is in width.

25 It is obvious that the button h or a similar device secured upon the inside of the plate H could be engaged by pins or spurs upon the bolts, so as to be protected against opening by the combination-lock. I therefore do not limit 30 myself to the exact devices shown.

I prefer to make my safe with a removable bottom plate, so that the outer chamber between the walls of the safe and box E may be filled from the bottom with fire-proof material; but 35 it may also be filled from the back, as safes are now usually filled.

I am aware that it is not new to arrange the solid bolts of a safe-door radially, so that they may be projected simultaneously from the corners of the door by means of devices located at 40 the center thereof; and I am also aware that it is not new to bevel the corners of the door and

door-frame of a safe, and I wish it understood that I do not claim either of these features *per se*.

What I claim as new, and desire to secure by 45 Letters Patent, is—

1. The combination, in a fire-proof safe, of air-chamber C, surrounding the inner receptacle, D, and the safe-door, having an inner air-chamber, which is also the receptacle for the 50 bolt-work, with tubular bolts to communicate with the chamber C and the chamber in the door when the safe is closed.

2. The combination, in a fire-proof safe, of the safe-body A and stepped door and door-frame with the inner receptacle, D, secured upon the inner flange or step of the door-frame, and the box E upon one of its intermediate steps or flanges, so as to form two chambers within the safe-body, the outer one for the 55 reception of a fire-proof filling, and the inner one being an air-chamber, substantially as specified.

3. The combination, with a safe having an air-chamber, and a door-frame the corners of the inner step of which are beveled and perforated opposite said air-space, of the door provided with an air-chamber, and having its inner step similarly beveled and perforated, the tubular bolts radiating from the center of the door, and adapted to be projected through 70 the beveled corners of the door and door-frame, and means for simultaneously projecting and retracting the bolts.

4. The combination, with the safe-door having a chamber, and the bolt-work arranged 75 within said chamber, of the inner door or plate, constructed to close said chamber, and provided with lugs adapted to be engaged by the bolt-work when the bolts are shot.

MAX MOSLER.
